BAKING MOLD FOR BREAD

Magnus Allan Holmqvist, 2-114 Amanuensvagen,
S-104 05 Stockholm, Sweden

Filed July 22, 1974, Ser. No. 490,642

Term of patent 14 years

Int. Cl. D7—02; D8—05

U.S. Cl. D7—96

Fig. 1

Fig. 3

Fig. 2

Fig.4

Fig.5

FIG. 1 is a perspective view of the baking mold for bread showing my new design;

FIG. 2 is a top plan view of the baking mold for bread;

FIG. 3 is a side elevational view of the baking mold for bread;

FIG. 4 is a bottom plan view of the baking mold for bread; and

FIG. 5 is a front elevational view of the baking mold for bread.

I claim:

The ornamental design for a baking mold for bread, as shown.
